Harry Van Buren, Dallas, Tex.

Application May 24, 1949, Serial No. 95,007

4 Claims. (Cl. 120—31)

1

The object of my present invention is to provide an improved copy holder the various units of which are cast from light alloys and which are so associated as to afford simple disassembly for storage or shipment.

Another object of my invention is the provision of a copy holding machine which when assembled and set up for use may be collapsed to the height of a typewriter and need never be removed from the operator's desk unless so desired.

A further object of this invention is to present a simplified machine in which one paper holding feed roller consists of a magnifying tube which acts as a copying line guide.

Still another object of this device is the provision of a copy holder wherein the operating force necessary to advance the paper may be adjusted to the desired touch of the copyist and wherein the momentum of the operating lever is retarded or damped by an attached air cylinder or dashpot.

Another purpose of my present invention is to provide a copy holding machine so constructed as to permit operation by the little finger of the typist without the necessity of removing the hand from typing position on the keyboard of the typewriter.

Still other objects and advantages will become apparent from the following description of the present invention illustrated in the accompanying drawing in which:

In the drawings:

Figure 1 is a front elevation of a copy holder embodying my invention shown with its panel in the raised position.

Figure 2 is a rear elevation of the copy holder as shown in Fig. 1.

Figure 3 is an elevation of the copy holder as seen when viewing the right hand side of Fig. 1.

Figure 4 is a sectional view taken on line 4—4 of Fig. 2.

Figure 5 is a fragmentary sectional view taken on line 5—5 of Fig. 2 and showing the operating lever mechanism.

Figure 6 is a sectional view taken on line 6—6 of Fig. 2 showing the bail roll and paper release embodied in the copy holder.

Figure 7 is a sectional view taken on line 7—7 of Fig. 2 showing the paper advancing pawl and racket in operative engagement.

Figure 7A is a partial view of the advancing mechanism shown in Fig. 7 with the parts disengaged.

Figure 8 is an exploded perspective view showing the means for detachably interlocking the copy feed arm and its pitman.

2

Figure 9 is a vertical cross sectional view taken on the line 9—9 of Fig. 5.

Figure 10 is an enlarged plan view of the panel locking structure.

Similar reference characters in the several figures indicate similar parts.

Referring first to Figs. 1 and 2 of the drawings it will be seen that the base portion of my copy holder is L-shaped and comprises a cast cross piece 10 to which there is fitted at one end another casting 11 which extends forwardly (Fig. 3) said parts, which when the device is in operating position, will enclose the rear and right hand edges of a typewriter. The section 10 has integrally formed on its left hand end a short cross piece 12 supported on rubber discs 13 for contact with a desk top. The opposite end of section 10 is rabbed at 14 to receive the rear end of the forwardly extending longitudinal section 11, these mating sections being secured together by the bolt assembly 15.

The section 11 consists of a horizontal base plate 16 (Figs. 3 and 5) having a vertical flange 17 at its outer longitudinal edge, the rear end of which is formed with a vertically projecting loop 18 to provide an elongated eye or opening 19 the purpose of which will be later explained. Rubber discs 13' on the bottom surface of plate 16 at its ends cooperate with the previously mentioned discs 13 to provide the copy holder with a non-skidding surface contact which prevent marring the finish of the desk top.

The cross piece 10 of the base of my device carries a pair of vertical guide rods 20. Reduced threaded ends of these rods pass through apertures in the section 10 and are rigidly secured in place by nuts 21. Movable positioned on the guide rods 20 is a panel 23 which has perpendicular side flanges 24 and similar top and bottom horizontal flanges 24^a which project rearwardly to form a shallow box-like structure. The rear faces of said flanges are provided with a plurality of small threaded holes 25 to enable the attachment of a closure plate (not shown) over the open side of the panel box to prevent undue collection of dust on operating parts contained therein and to increase the neatness and attractiveness of the device in general. Bosses 26 are provided to give body to the flanges 24 at points selected for the location of the threaded holes 25.

The panel 23 is shown in Figs. 1, 2, 3 and 4 in a raised position on the guide rods 20. It is this position that is assumed when the copy holder is in use. In order to maintain the panel assembly in the raised position, I have provided a locking bar 27 having a horizontal flange 31,

which is supported in slots 28 (Fig. 4) passing through side flanges 24 and the bosses 29 attached thereto and to the rear face of panel 23. The bosses 29 are provided with apertures receiving the upper ends of the rods 20 and the ends of the rods carry stops which may be cotter pins 30 to limit the upward movement of the panel box once it is assembled on the guide rods.

Near the upper ends of rods 20 are horizontal notches 20^a, shown in Fig. 10, cut into the right hand sides thereof, as viewed in Fig. 2. These notches are of sufficient depth to accommodate a portion of the peripheral edges of elliptical apertures 31^a in the opposite ends of the horizontal plate 31 of the locking bar 27. From this it will be seen that when the bar 27 is in the position shown in Fig. 2 the edge of each elliptical aperture of the bar will engage its respective notch and thus prevent any vertical movement of the panel. For automatically engaging the locking bar 27, when the panel has been raised to its normal upward position, there is a coil spring 32 connected to the bar and to an apertured protuberance 33 on the inner face of panel 23. The spring as thus positioned is placed under tension and as a result constantly tends to force the bar 27 into locking engagement with the notches or to the left as viewed in Fig. 2.

When it is desired to lower the panel 23 to an inoperative and compact position the tab 34 on the end of the locking bar is depressed to disengage the bar from the notches in the guide rods 20 whereupon the panel is forced downwardly carrying the bar with it by coil springs 35 which were compressed under the momentum created in raising the panel previously. The entire panel assembly being then free may be moved downwardly to its collapsed position where its upper edge will be below the top of the typewriter where it will not interfere with further activity of the typist.

In order to hold the material to be copied firmly against the front face of panel 23, I prefer to use a combination paper holder and magnifying line guide. This assembly consists of a liquid-filled glass tube 36 extending horizontally across the front of the panel 23. Each end of the tube 36 is enclosed by a metallic cap 37 with an axial nipple 38 thereon. The nipple at the right extremity of the magnifying tube, as viewed in Fig. 1, is received in an aperture formed in the upper end of a pivot arm 39. The opposite nipple 38^a on the left side of tube 36 is inserted into a longitudinal slot 38^b in the upper end of a second pivot arm 40. The latter nipple is rotatably secured within this slot by means of a pivoted latch 41 which is slotted to provide a projecting finger 41^a to fit over the nipple and close the open end of the slot. The latch 41 may be pivoted forward by means of the finger tab 42 permitting the magnifying tube 36 to be easily removed for repair or replacement if necessary.

Pivot arms 39 and 40 are secured to the outer ends of elongated pins 43 by means of screws 44. The outer end of each pin 43 passes through an aperture in the side flange 24 of the panel box and carries a spacing washer 45 for relatively positioning each pivot arm 40 from its proximate panel box flange 24. The inner ends of the pins 43 are supported by apertured bosses 46 formed on the rear face of panel 23. Each pin is surrounded by a coil spring 47 one end of which passes through a slot (not shown) in the pin and the other end of the spring presses against the surface of the panel 23. The springs 47 are so

positioned as to be placed under a twisting tension and therefore constantly urge the tube 36 toward the front surface of the panel to provide a holding force against the papers carried by the device. Thus the tube 36 has the dual function of holding the copy material in position and of magnifying each line of print as it moves behind the tube.

Means are provided to relieve the holding force exerted by the tube in order to remove or adjust the copy material as occasion may arise. To accomplish this end I use a paper release lever 48 which is secured to one end of an oscillatory cam rod 49 by means of the screw 50, as shown in Fig. 6. The rod 49 lies adjacent the rear face of panel 23 and is supported at its ends in apertures provided in the side flanges 24. At points opposite pivot arms 39 segmental slots are cut in the cylindrical surface of the rod so that when lever 48 is rotated in either direction the edges of the slots act as cams to move the arms away from the panel 23 thereby spacing in an outward position relative to the tube 36. When it is desired to renew the holding effect of the tube assembly the release lever is returned to its original position whereupon the pivot arms 39 once more enter their respective slots in the cam rod 49.

Feeding the paper comprising the copy is accomplished by a transverse cylindrical rubber roller 51, the forward edge of which protrudes through an elongated opening 52 in the panel 23 into cooperative relation with the tube 36 when the latter is in the holding position. Said roller is supported by journaling the ends of its central core rod 53 in apertures in the side flanges 24 of the panel box.

A ratchet wheel 54 is attached to one end of the rod 53, the wheel being provided with an inner hub 55 acting to space the wheel to assure proper clearance between it and the proximate end of the paper holding and feeding assembly previously mentioned.

On a similar hub on the outer face of the ratchet wheel 54 an oscillatory arm 56 is journaled which is held in position by a knurled abutment nut 57.

As will be seen in Fig. 7, the free end of arm 56 carries a pawl 58 which engages the peripheral teeth of the ratchet wheel to rotate it and feed roller 51. The pawl 58 is connected to the arm by means of a pivot screw 59 and is tapered as at 60 to conform to the outline of the lower edges of the arm to prevent the presentation of unnecessary projecting edges which might catch in the clothing of the typist. Surrounding the pivot screw 59 is a coil spring having an end 61 which extends into a small hole 62 in the arm while its opposite end 63 extends over the top of the pawl to urge the same into engagement with the teeth of the sprocket.

Should it be desired to manually reverse the rotational direction of the rubber roller 51 and thus lower the copy sheet on the panel, the pawl release knob 64 may be turned to rotate a semi-cylindrical cam 65 which will hold pawl 58 out of engagement with the sprocket teeth. As seen in Fig. 7A the ratchet wheel is thus free to revolve in either direction.

Vertical reciprocation of the oscillatory arm 56 is effected by the manipulation of an actuating lever 66 by the typist. The forward end of the actuating lever is provided with a curved finger key 67 offset from the plane of the lever as shown in Fig. 1. This offsetting feature of the key 67 allows it to be positioned in proximate relation

with keys of the typewriter thereby permitting the operator to depress said finger key without removing her hand from typing position over the keyboard. The actuating lever 66 is pivoted near its center on the shank of a bolt assembly 68 which passes through the vertical flange 17 of the base section 11.

A vertical arm or pitman 69 is joined at its lower end to the lever 66 by a swivel pin 70 and at its upper end to the arm 56. This latter connection is effected by means of a projecting pin 71 (Fig. 8) carried by the arm 56 and which is received within an aperture 72 formed at the upper end of the arm 69. The arm is held in place on the pin 71 by means of a U-shaped snap spring 73 fastened to the outer side of the arm by a screw 74. The free ends of the spring 73 extend through recess openings 75 formed in the front and rear peripheral faces of a boss 76 on the upper end of arm 69 and engage a peripheral groove on the outer end of pin 71 thereby retarding outward movement of the toggle arm on the pin. The outer edge of the pin groove is beveled to permit the disassociation of the arm and pin 71 with a slight force exerted by the typist when it is desired to collapse the panel assembly as heretofore explained. The toggle arm when released from its operative position, may be lowered to an unobstructing position as shown in Fig. 5.

The ultimate amount of each arcuate movement of the paper-conveying rubber cylinder 51 is controlled by means of a space regulating assembly 77 (Fig. 9). This regulator is adjustable to limit the extent of depression of the operating lever 66 in order to precisely position each successive printed line of the copy material behind the line guide 36 with each actuating stroke by the copyist.

The horizontal plate 16 is provided with a shallow groove 18 to position a support member 19 firmly attached to the plate by a screw 80. The support member has an overhanging shelf 81 projecting from its upper end and in which is journaled a carrier screw 82. The lower end of the screw 82 passes through an aligned aperture in the plate 16 and is provided with a detachable abutment head 83 to restrain the carrier screw assembly from vertical movement.

An internally threaded metallic stop piece 84 and a superposed rubber pad 85 are carried by the screw and are reciprocated in their vertical confine by manipulation of the knurled knob 86 formed integrally with the screw. As seen in Figs. 1 and 9 a coil spring 87 surrounds a portion of the screw and is confined between the collar 81 and the rubber pad 85 to provide sufficient frictional force between the parts to prevent accidental movement of the adjusted assembly.

When the finger key 67 of the operating lever is released from the depressed position, shown dotted at 88 in Fig. 3, the combined weight of the arm 69 and the contracting force of a light coil spring 89 acting on the rear end of lever 66 (Fig. 5) returns the rear end of the lever to its initial resting place on the base portion 11 of the copy holder.

In operating the spacing lever 66 it may gain momentum on either the driving or return stroke which ordinarily would result in a jarring and noisy impact between certain metallic parts of the device. To obviate this undesirable occurrence I have provided on the lever a small air cylinder 90 to act as a governor to dampen the stroke, the cylinder being pivotally supported on

the lever by a projection 91. The piston in cylinder 90 is carried on a piston rod 92 suspended from the upper rim of the projecting loop 18 by a laterally extending pin 93.

Hence it will be seen that the small amount of compression within the air cylinder effectively slows the movement of the mechanism to assure a smooth and noiseless operation of the machine in each direction.

10 A further control of the actuating lever 66 is provided by a frictional adjustment arranged for the rubber feed roller 50. This is accomplished by threading on the end of the roller rod 52 a knob 94 shown in Figs. 1 and 2. The knob 15 has a boss 95 on the inner face thereof which may compress a spacing collar 97 against a coil spring 96 the inner end of which engages the panel flange 24. By screwing the knob 94 tighter the spring is compressed creating a friction which 20 retards the rotation of the paper conveying roller assembly. Thus it will be seen that by regulating this frictional force the actuating lever will be accordingly adjusted to the desired touch of the copyist. Once correctly positioned the knob 25 94 may be secured in place by the set screw 98 shown in Fig. 1.

On the opposite end of the transverse rod 52 I have shown a second knob 99 removably attached to the rod by means of a set screw 100. 30 This knob may be used for manual operation of the paper conveying mechanism independent of the previously described ratchet and pawl assembly.

35 The upper portion of my copy holding panel is provided with a bail roll assembly 101. This assembly consists of the transverse bar 102 and a rearwardly extending arcuate fin 103 secured thereto. The bar is connected at its axial extremities to a pair of supporting arms 104 by means of holding screws 105. Supporting arms 104 are in turn pivotally attached to the side flanges of the panel box by pivot screws 106. The downward swing of the bail roll is limited by small abutment screws 107 carried by the side flanges 24.

40 It is apparent from Fig. 6 that in its normal forward position the bail roll will automatically turn the copy backward and prevent the same from falling forward to obstruct the line of vision. 45 Since the bail roll shown in the drawings is movable, the operator is allowed to copy from a number of sheets which are fastened together without tearing them apart. By merely rotating the bail roll to its backward position and releasing the paper holder, the sheets can be backed through the machine to a starting point.

45 From the foregoing description of my present invention it will be seen that I have provided a compact and light weight copy holder which possesses the advantages of ease of operation, simplicity and durability. Furthermore by casting the panel and its supporting frame from a light weight alloy the need for spot welding and various other mechanical operations is avoided.

50 This device affords a convenient means for advancing material to be copied with the desired touch of the typist and without the necessity of removing the hand from the keyboard of the typewriter, this operation being accomplished with a minimum of noise and jar by the cooperating parts of the device.

55 While a preferred form of the invention has been shown and described, it will be understood 70 that variation in details of form may be made

without departure from the invention as defined in the appended claims.

I claim:

1. In a copy holder, a combination with an L-shaped base composed of a rear cross piece and a forwardly extending lateral piece both being of cast metal and mortised at their overlapping ends, and vertical guide rods on the rear piece, of a cast metal panel having rearwardly extending flanges guided on the rods, an adjustable cross bar slidably retained by said panel and extending beyond the sides thereof, said bar interlocking with the rods to hold the panel in elevated position, spring means connecting said panel and rods biasing the panel to a non-elevated position, cooperating paper feed rolls on the panel, a ratchet on one of the rolls, a pawl for operating it, a spacing lever on the lateral base piece, an arm extending vertically from its rear end for actuating the ratchet, and a rotatable cam member for selectively preventing engagement between said pawl and ratchet.

2. In a copy holder, the combination with an L-shaped base composed of a rear cross piece and a forwardly extending lateral piece both being of cast metal and mortised at their overlapping ends, and vertical guide rods on the rear piece, of a cast metal panel having rearwardly extending flanges guided on the rods, an adjustable cross bar in rear of the panel interlocking with the rods to hold the panel in elevated position, cooperating paper feed rolls on the panel, a ratchet on one of the rolls and a pawl for operating it, a spacing lever on the lateral base piece and an arm extending vertically from its rear end for actuating the ratchet, and a rotatable cam member for selectively preventing engagement between said pawl and ratchet.

3. In a copy holder, the combination with an L-shaped base composed of a rear cross piece and a forwardly extending lateral piece both being of cast metal and mortised at their overlapping ends, and vertical guide rods on the rear piece, of a cast metal panel having rearwardly extending flanges guided on the rods, an adjustable cross bar slidably retained by said panel and extending beyond the sides thereof, said bar interlocking with the rods to hold the panel in

elevated position, spring means connecting said panel and rods biasing the panel to a non-elevated position, cooperating paper feed rolls on the panel, a ratchet on one of the rolls, a pawl for operating it, a spacing lever on the lateral base piece, an arm extending vertically from its rear end for actuating the ratchet, and a rotatable cam member for selectively preventing engagement between said pawl and ratchet.

4. In a copy holder adapted to be mounted in rear of a typewriter, the combination with a base, guide rods thereon and a vertically adjustable two position panel thereon in one position being hidden behind the typewriter and the other being elevated in copy holding position, and releasable locking means on the panel cooperating with the rods for holding it in copying position, of copy feeding rolls on the upper portion of the panel, a ratchet on one of the rolls, a pawl cooperating therewith, and an oscillatory arm carrying the pawl, a spacing lever, an upwardly extending arm on the lever and a spring clip connection between the upper end of the upwardly extending arm and the oscillatory arm for disconnecting said parts to enable the panel to be adjusted downwardly into the first mentioned position.

HARRY VAN BUREN.
